United States Patent Office

Des. 182,980

Patented June 3, 1958

182,980

HAND TOOL

Herbert C. Stoltz, Palmyra, Pa.

Application April 26, 1957, Serial No. 45,898

Term of patent 14 years

(Cl. D54—13)

I claim:

The ornamental design for a hand tool, substantially as shown.
